DESIGN FOR A PITCHER

Charles W. Sawyer, Toledo, Ohio, assignor to Libbey Glass Company, Toledo, Ohio, a corporation of Ohio

Application September 25, 1941, Serial No. 103,493

Term of patent 7 years

To all whom it may concern:

Be it known that I, Charles W. Sawyer, a citizen of the United States, residing at Toledo, in the county of Lucas and State of Ohio, have invented a new, original, and ornamental Design for a Pitcher, of which the following is a specification, reference being had to the accompanying drawing, forming a part thereof.

On the drawing the figure is a perspective view of a pitcher, showing my new design.

I claim:

The ornamental design for a pitcher, substantially as shown.

CHARLES W. SAWYER.
